UNITED STATES PATENT OFFICE.

CHRISTIAN F. DILG AND CHARLES H. J. DILG, OF NEW YORK, N. Y.

CUTLERY-POLISHING MACHINE.

SPECIFICATION forming part of Letters Patent No. 662,919, dated December 4, 1900.

Application filed July 3, 1895. Serial No. 554,903. (No model.)

To all whom it may concern:

Be it known that we, CHRISTIAN F. DILG and CHARLES H. J. DILG, citizens of the United States, and residents of New York, in the county and State of New York, have invented a certain new and useful Cutlery-Polishing Machine, of which the following is a specification.

Our invention relates to a cleaning and polishing machine adapted for use primarily for renovating articles of small size, as knives, forks, &c., or other cutleryware, and has for its object the provision of a machine of the class described simple in construction, inexpensive in manufacture, and efficient in practical use.

To attain the desired end, our invention consists in the construction, arrangement, and operation of parts hereinafter set forth. Figure 1 represents a plan view of a machine constructed according to our invention. Fig. 2 is a vertical transverse section of the same, taken on the line 2 2, Fig. 1. Fig. 3 is a view of the bottom of our machine. Fig. 4 is a transverse section of our base or bed plate. Fig. 5 is a partial side elevation of the said base. Fig. 6 is an end view in detail of our machine, and Fig. 7 is a detail of our knife-rest.

Referring particularly to the drawings, A denotes the bed or base framework of our machine, which is provided with two high posts A' and three small posts A² and with three front slots a a' a'' and one rear slot a². The base A also supports a central roller A³, which prevents the knife from being tilted. Mounted upon the base A is our roller-inclosing frame or shell B, provided upon the central portion of its rear and front faces with lugs b, which serve to adjustably support by means of screws b² the rotatable knife-rests B', provided with cushioned tops b', made of any suitable material, as of leather.

C represents our carriage, provided at one end with an adjusting-screw C², passing through an orifice in the side of our bed A, and at the other with two posts C', located at opposite sides of the end C³ of our carriage, and also with a transverse extension C⁴, provided with a plate C⁶, resting on top of the bed A and connected with the carriage C by means of a flat post C⁷, working in a slot a''

of the said bed A. The plate C⁶ is provided with a bifurcated vertical portion C⁵. The posts C' rest and travel upon the top of our bed-plate A, the lower thinner portions of the said posts C', adjacent to the carriage C, passing through the narrowed parts of the slots a' a².

The posts A' support a horizontal shaft H, and the posts C' support a similar shaft H'. These shafts are provided with pins h and h', which lie in recesses of the hubs of the interchangeable disks L, secured together by screws L', located on both sides of our wheels J J' K K', constructed of flexible or elastic material, as of rubber, the said hubs abutting or running against the journals formed by the posts A' and C'.

Our wheels J J' K K' are ordinarily faced with flexible material, as j j', preferably consisting of leather and ordinarily coated with emery, rottenstone, or any suitable cleaning or polishing powder.

The front post A' carries two gear-wheels—namely, an upper gear-wheel G and a lower bevel-gear F, meshing into gear G—and the front post C' of the carriage C also carries two gear-wheels—namely, an upper gear G' and a lower bevel-gear F', meshing into the gear G'. A shaft D crosses the front of our machine, to be out of the path of the knife, and is provided with an operating-handle D' and with a rigid bevel-gear E, which meshes with the bevel-gear F and also with a loose bevel-gear E', the hub of which works on the key d. The bevel-gear E' meshes with the bevel-gear F' of the post C' and is held adjacent thereto by means of the bifurcated vertical extension C⁵ of the carriage C. The rest M is secured to the shell B by means of the screw m. A sectional buff or brush, consisting of the wide layers or disks N and narrow ones n, is carried by a shaft D², which is provided with a bevel-gear d², which meshes with the bevel-gear d³ of the shaft D. The pawl g, adjacent to the bevel-gear G, prevents the parts from being turned the wrong way.

A trough Q is secured to the bed A by a screw q² and is provided with notches q, which serve as knife-rests whereby to evenly grind knives when an emery-wheel is placed on the shaft D².

It is manifest that various omissions of some particulars could be made without materially affecting the essential features of our invention or the operation of the remaining 5 parts, and we do not therefore wish to be limited to the specific structural details of the organization herein set forth. Obviously the elements of the structure described may be located at an angle to the plane in which 10 they are shown, or they may be inverted, if desired. We accordingly use the words "vertical," "horizontal," and the like in a relative sense.

In operation the article to be renovated, as 15 the knife O, is placed between the wheels J J' K K', (the rests B' serving to keep the same level,) and upon turning the handle D' and drawing the knife through the machine the same will be found to be cleaned and polished. The rests B' may be raised or lowered, according to whether a wide or narrow 20 knife is used, and any excessive wear of the leather tops of the same is avoided by the fact that the said tops are rotatable. In cases 25 where thin knives are to be cleaned the elastic wheels K K' may be caused to approach the wheels J J' by manipulating the screw C², the adjacent peripheries of the same becoming thereby flattened. The wheels K K' will 30 be operated in any position (contiguous or adjacent) by means of the handle D' on account of the fact that the gears G', F', and E' travel with the carriage C. When not in use, the wheels K K' may be drawn away from 35 the wheels J J'. Guards P P' are used to cover the bevel-gear in order to prevent danger of injury to the hand of the operator.

Forks, as T, may be polished by holding the same against the leather facing of our 40 rubber wheels or tires by use of the rest M, or the sectional buff or brush N n may be used in order to clean the interior of the tines of the same. By resting the back of a knife in one of the notches q of the trough or cup 45 Q the edge of the same may be ground against an emery-wheel R.

As it is evident that many changes in the construction and relative arrangement of parts might be resorted to without departing 50 from the spirit and scope of our invention, we would have it understood that we do not restrict ourselves to the particular construc-

tion and arrangement of parts shown and described, but that we reserve the right to make such changes, and that

55

What we claim as new, and desire to secure by Letters Patent, is—

1. In a cutlery-polishing machine, the following elements; shafts of two rotatable cleaning devices, means to move one shaft forward and backward (parallel to the other) and rigidly hold the same in any desired position; a main operating-shaft located below the plane of the two said shafts; and stationary and shifting means to similarly rotate the stationary and movable shafts in opposite directions whether the same are moving forward or back or lying adjacent or apart; and detachable rotatory cleaning devices.

2. In a cutlery-polishing machine, the following elements; shafts of two rotatable cleaning devices, one shaft mounted in a movable carriage constructed and arranged to contain the cleaning devices the other shaft being supported directly by the base of the machine; means to move one shaft forward and backward (parallel to the other) and rigidly hold the same in any desired position; stationary and shifting means to similarly rotate the stationary and movable shafts in opposite directions whether the same are moving forward or back or lying adjacent or apart; and detachable rotatory cleaning devices.

3. In a cutlery-polishing machine, the following elements; shafts of two rotatable cleaning devices, means to move one shaft forward and backward (parallel to the other), and rigidly hold the same in any desired position; stationary and shifting means to similarly rotate the stationary and movable shafts in opposite directions, whether the same are moving forward or back or lying adjacent or apart; detachable rotatory cleaning devices and means located above and intermediate of said shafts to support the article to be cleaned.

In testimony of the foregoing specification we do hereby sign the same, in the city of New York, county and State of New York, this 23d day of February, A. D. 1893.

CHRISTIAN F. DILG.
CHARLES H. J. DILG.
